William Rosenthal, Pacoima, Calif.

Application December 10, 1954, Serial No. 33,473

Term of patent 7 years

(Cl. D48—20)

To all whom it may concern:

Be it known that I, William Rosenthal, a citizen of the United States of America, residing in Pacoima, in the county of Los Angeles, State of California, have invented a new, original, and ornamental Design for Combined Lamp Base and Reflector, of which the following is a specification, reference being had to the accompanying drawing, forming a part thereof.

Fig. 1 is a perspective view of a combined lamp base and reflector, showing my new design, the broken lines indicating a shade being for illustrative purposes only; and

Fig. 2 is a side elevational view of the same.

I claim:

The ornamental design for a combined lamp base and reflector, substantially as shown and described.
